(57) **CLAIM**

The ornamental design for a planar electrical connection interface port, as shown and described.

DESCRIPTION

FIG. 1 is a top, left, and front perspective, view of a planar electrical connection interface port, in use condition, showing our new design;

FIG. 2 is a bottom, left and front perspective view thereof;

FIG. 3 is an exploded top, left, and front perspective view thereof;

FIG. 4 is an elevated top, left, and front perspective view thereof;

FIG. 5 is a front, elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The broken lines in the figure drawings are included to show unclaimed environmental and form no part of the claimed design.

UNITED STATES PATENT AND TRADEMARK OFFICE
CERTIFICATE OF CORRECTION

PATENT NO. : D689,823 S
APPLICATION NO. : 29/430154
DATED : September 17, 2013
INVENTOR(S) : van Beveren et al.

Page 1 of 1

It is certified that error appears in the above-identified patent and that said Letters Patent is hereby corrected as shown below:

Title Page

Item (73), Assignee, change “Dirtt Environment Solutions, Ltd.” to --DIRTT Environmental Solutions, Ltd.--

Item (56), Other Publications, change “filed Jun. 5, 2009).” to --filed Jun. 5, 2009), Examiner E. R. Ring (Received March 9, 2010).--

Item (57), under Description, include --BE IT KNOWN that We, Steven M. van Beveren and Henry A. Roemer have invented a new, original, and ornamental design for a planar electrical connection interface port, as set forth in the following specification, reference being made to the accompanying drawings which form a part thereof. The claimed planar electrical connection interface port is designed to receive and mate with a planar electrical connector--

Item (57), Claim, change “interface port, as shown and described” to --interface port as shown and described--

Item (57), Description, Figure 1, change “perspective, view” to --perspective view--

Item (57), Description, under Figure 10, change “unclaimed environmental” to --unclaimed environment--

Signed and Sealed this
Fourth Day of February, 2014
